ABRASIVE BELT RETAINING ASSEMBLY

Leo C. Bogaerts, Antioch, Ill., assignor to Ammco Tools, Inc., North Chicago, Ill., a corporation of Illinois
Filed Jan. 25, 1962, Ser. No. 168,638
2 Claims. (Cl. 51—181)

This invention relates to assemblies employing abrasive belts, and is directed more particularly to such assemblies in which the abrasive belt is wrapped around a rotatable cylinder or arbor for grinding and like purposes.

Heretofore difficulty has been encountered in securing abrasive belts to such arbors. Unless properly held to the arbor, the belt will not remain properly aligned in a grinding position on the arbor during operation of the assembly. Also, if worn by use, both the belt and the hooks thereon had to be scrapped.

With the present invention, the problems and difficulties of the prior art are substantially overcome by the provision of hooks having thermoplastic spikes or rivets thereon which pass through openings in the ends of the belt. The ends of the rivets protruding through the belt are heated and bent over to lock or heat weld the hooks in position securing the belt, the belt being mounted on the arbor with the ends thereof in a slot formed in the arbor, and the hooks then separately clamped by clamping members mounted to the arbor in the slot to secure the belt in position on the arbor. In this manner each end of the abrasive belt is provided with a flange member or "hook" secured thereto by plastic rivets and is separately clamped in spaced relation to the other hook by the clamping members in the slot formed in the arbor. The belt hooks thus facilitate assembly and disassembly of the belt to the arbor. Thus, with the present invention, the problems of securing the belt ends to the hooks, the hooks in the arbor slot and the belt to the arbor, are simplified. Moreover, when it becomes necessary to replace the abrasive belt, the cost occasioned by replacement of low cost and easily manufactured plastic hooks is generally a small percentage of the replacement cost of comparable metal hooks.

It is therefore an object of the present invention to provide an abrasive belt assembly which is capable of being easily and inexpensively manufactured.

Another object of the present invention is to provide new and improved clamping hooks for attachment to the ends of a split abrasive belt, said hooks having heat deformable belt attaching members constructed of a plastic material.

Still another object of the present invention is to provide a clamping assembly for locking an abrasive belt in position on a cylinder including hooks constructed of a plastic material and having heat deformable thermoplastic spikes thereon which pass through the ends of the belt and which are heat deformed and bent over against the belt to secure the hooks to the belt ends.

A further object of the present invention is to provide a split belt having an abrasive surface which is adapted to be wrapped around a cylinder and held in position on the cylinder by plastic hooks secured to the ends of the belt by plastic rivets, the ends of which pass through the belt and are heat deformed and bent over against the belt to secure the hooks to the belt.

Another object of the present invention is to provide a new and improved assembly for securing the ends of a belt, wrapped around a cylinder, in clamping means.

These and other objects, features and advantages of the present invention will become readily apparent from a careful consideration of the following detailed description, when considered in conjunction with the accompanying drawings wherein like reference numerals and

2

characters refer to like and corresponding parts throughout the several views, and wherein:

FIG. 1 is a top view of an illustrative form of a brake lining groover, including an abrasive belt, constructed in accordance with the principles of the present invention.

FIG. 2 is a side view in partial section of the groover of FIG. 1 taken along line 2—2 of FIG. 1.

FIG. 3 is a fragmentary view in elevation of the groover of FIG. 1 illustrating the grooving tool employed with the lining groover.

FIG. 4 is a view in elevation of a retainer or hook for attaching an end of an abrasive belt in the arbor slot of the groover of FIG. 1.

FIG. 5 is a view illustrating the hook of FIG. 4 attached to an end of an abrasive belt by heat deformed plastic spikes.

Although the present invention has a variety of applications, a suitable environment therefor appears in my copending application, Serial No. 121,810, filed June 27, 1961, wherein is disclosed a brake lining groover, including a spindle upon which is mounted a cylindrical arbor for rotation with the spindle, and an abrasive split belt supported on the arbor which is adapted to rotate with the spindle and thereby grind the surface of a brake lining when brought into contact therewith. Both the arbor and abrasive belt are provided with aligned slots through which a tool bit may extend, the tool bit being rigidly supported on the spindle. The arbor is one embodiment disclosed in my above mentioned copending application is slotted to receive the end portions of the split abrasive belt. Clamping members, forming a belt retainer, are mounted in the slot to hold a pair of belt hooks, attached to opposite ends of the belt, in spaced relation on either side of the slot inward of the outer surface of the arbor. Each of the clamping members is provided with an aperture aligned with the slot of the arbor so that the tool bit extends from the spindle through the clamping member apertures and arbor slot with the bit thereof in position for grooving a brake lining.

Referring to FIGS. 1 and 2 there is shown a brake lining groover 8 which comprises an arbor 9 mounted on a spindle 10 adapted to be rotated by a source of power (not shown). Rigidly supported on the spindle 10 is a tool holder 12. The tool holder 12 is bored and slidably disposed on the spindle 10 as clearly appears in FIG. 2.

The tool holder 12 is provided with a bore 14 which extends perpendicularly to the axis of rotation of the spindle 10 and a locking dog 16 is slidably disposed within the bore 14. The dog 16 is maintained in contact with a flattened portion 18 of the spindle 10 by a set screw 20. The flat portion 18 of the spindle 10, the dog 16 and set screw 20 cooperate to positively lock the tool holder 12 to the spindle 10 thus fixing the relative angular position 55 of the tool holder 12 with respect to the spindle 10.

The tool holder 12 is provided with another bore 22 (FIG. 2) in which is disposed a tool bit shank 24 carrying a tool bit 26. A threaded set screw bore is drilled into the holder 12 and intersects the bore 22 at a right angle thereto. A set screw 28 disposed in the set screw bore of the holder 12 is provided which holds the tool bit shank 24 firmly in position in the bore 22. It will be appreciated that this arrangement of shank, holder bore 22 and set screw 28 permits limited axial movement of the tool bit 26 to and from a predetermined grooving position relative to the outer surface of the arbor 9.

The arbor 9 is formed with an integral bottom support member 30 (FIG. 2) secured for rotation to the spindle 10 by a roll pin 32 extending through aligned bores 33 and 33a in the spindle 10 and the support member 30.

The tool holder 12 is mounted on the spindle 10 in alignment with a longitudinal slot 36 formed in the arbor

9 so that the tool bit 26 is in position for movement inwardly of the outer surface of the arbor or outwardly of the outer surface of the arbor to and from a brake lining grooving position as well as for vertical movement relative to the axis of rotation of the spindle 10 for cutting liners in different locations.

The edges 38 and 40 of the arbor 9 defining the slot 36 are rounded as appeared in FIG. 1 to minimize friction damage thereby to spaced end portions 42 and 44 of a split abrasive belt 46 which is wrapped around the periphery of the arbor 9 and secured by the ends 42 and 44 thereof to a pair of clamping hooks 48 and 50 which are retained in the slot 36 in spaced apart relation by a clamping assembly 52 which is mounted on spindle 10 in the slot 36 inward of the external surface of the arbor 9 and which is provided to lock the abrasive belt 46 firmly on the periphery of the arbor 9.

To mount the clamping assembly 52 in the slot 36, the spindle 10 is provided with a pair of bores 56 and 58 (FIG. 2) in which a pair of screws 60 and 62 are threadably mounted, one screw 56 being located at the top of the arbor 9 and the other screw 58 being located near the bottom of the arbor 9. The screws 60 and 62 pass through complementary holes in the clamping members 52a and 52b.

Each of the clamping members 52a and 52b is wing-shaped in configuration. The exterior clamping member 52b is provided with two inwardly directed clamping elements and the interior clamping member 52a is provided with two U-shaped clamping elements 53 and 55 positioned so as to receive the inwardly directed clamping elements of the exterior clamp member 52b.

The screws 60 and 62 are provided with retaining heads 64 and 66 which retain the clamping members 52a and 52b inward of the outer surface of arbor 9 in slot 36. A pair of springs 68 and 70 mounted on the screws 60 and 62 respectively hold the clamping members 52a and 52b together against the screw heads 64 and 66 to urge the clamping assembly 52 to a predetermined clamping position relative to the spindle 10.

Each of the clamping members 52a and 52b is provided with a rectangularly shaped aperture, 67 and 69 (FIG. 2) having vertical edges 70 and 71 and horizontal edges 72 and 73. The apertures defined by clamping members 52a and 52b are axially aligned with the slot 36 formed in the arbor 9. The apertures so formed in the members 52a and 52b permit the tool shank 24 and bit 26 to extend through slot 36 beyond the outer surface of the abrasive belt 46 for grooving of a brake liner. The apertures in the members 52a and 52b are also of a width sufficient to permit a wide vertical adjustment of the position of the tool holder 12 on the spindle 10 to permit positioning of the bit 26 for grooving brake liners in different locations.

A feature of the present invention resides in the new and improved hook members or hooks 48 and 50 which are provided to facilitate clamping of the abrasive belt 46 in the arbor 9. Since these hooks 48 and 50 are identical in construction and operation and may be used interchangeably for securing thereof to either end 42 or 44 of the belt 46, the description now to follow will relate to hook 50, it being understood that the description thereof is equally applicable to a description of the construction and operation of the hook 48.

As appears in FIG. 4, the hook 50 comprises a body portion 80 having a plurality of spikes or rivets 82 outstanding thereon which extend preferably at an angle to the body portion 80. The rivets or spikes 82 are constructed of a thermoplastic material, preferably a synthetic plastic, such as nylon, although it will be understood that any thermoplastic material having sufficient strength and rigidity may be employed in the formation of the spikes or rivets 82. The spikes or rivets 82 are each frusto-conical in configuration with the end portion thereof adjacent the body 80, being of greatest diameter. The

spikes or rivets 82 are preferably staggered to provide an efficient holding arrangement when the outer ends 84 thereof are deformed by heat to secure the belt 46 to the hook 50 as appears in FIG. 5. Preferably the entire hook 50 is formed of the same material.

The belt 46 is provided at both ends 42 and 44 with a plurality of openings 86 through which extend the spikes or rivets 82. The hook rivets 82 appearing in FIG. 4 have not as yet been bent over and deformed by heat to lock the belt to the hook body 80. For purposes of illustration, a pair of plastic rivets 82 are shown in FIG. 5 with their ends 87 deformed by heat to emphasize the manner in which the rivets 82 are bent over against the belt 46 when heat deformed to lock the belt 46 to the hook body 80.

After the ends 84 of the rivets 82 have been heat deformed and thus bent over against the belt 46 to form the rivet heads 87 (FIG. 5) and after the spikes or rivets 82 of the hook 48 have been so heat deformed to the other end 44 of the belt 46, the belt 46 is now ready to be mounted to the arbor 9. The body portion 80 of each of the hooks 48 and 50 is provided with an arcuate portion 90 terminating in a longitudinally extending end flange 92 which is to be clamped between the clamping members 52a and 52b as appears in FIG. 1. The hooks 48 and 50 may be constructed of any suitable material such as a plastic, and a preferred form of hook body 80 is formed of nylon. If other suitable material is employed in the construction of the hooks 48 and 50 the plastic spikes or rivets 82 are suitably mounted on such material.

In mounting the belt 46 to the arbor 9, the clamping members screws 60 and 62 are loosened to permit insertion of the flanges 92 of each of the hooks 48 and 50 between the clamping members 52a and 52b. The sleeve belt 46 is slid longitudinally over the arbor 9 and the end flanges 92 of the belt hooks 48 and 50 inserted longitudinally between the clamp members 52a and 52b until the belt 46 is longitudinally positioned on the arbor 9 by indexing the edge 46a of the belt 46 against an annular flange shoulder 30a of the bottom support member 30.

The screws 60 and 62 are then tightened to stretch the abrasive belt 46 over the arbor 9 and at the same time to increase the pressure between the clamping members 52a and 52b on the flanges 92 of the hooks 48 and 50 by compression of the springs 68 and 70.

In operation, a brake shoe (not shown) is positioned in a clamp (not shown), and the brake shoe groover of the present invention brought into engagement with the lining on the brake shoe and then rotated about the shoe while the spindle 10 is turning. The means for bringing the groover into engagement with the brake shoe, and for rotating it, may be any of a number of traversing devices well known in the art and such devices do not constitute a part of the present invention. The tool bit 26 will cut a groove in the brake shoe lining at the required position. The groove will be cut to a predetermined depth determined by the cutting edge of the tool bit 26, with respect to the surface of the abrasive belt 46.

After a groove has been cut in the brake lining to the predetermined depth, the abrasive belt 46 will then begin to grind the brake lining to form its surface to the correct degree of convexity so as to cooperate with its associated brake drum. This curvature results when the brake shoe is pivoted about a point distant from the lining to be ground by an amount which is equal to the radius of the brake drum, so that at the completion of the grinding operation, the surface of the brake lining on the brake shoe will exactly correspond to that of its associated brake drum.

During the period in which the abrasive belt 46 is shaping the lining the cutting edge of the tool bit 26 continues its grooving function, cutting always a groove at exactly the same depth, as determined by the amount of penetration of the cutting edge of the bit 26 beyond the outer surface of the abrasive belt 46.

When the lining has been properly shaped and grooved, the operation of the brake lining groover is discontinued and the brake shoe is then ready for assembly in the brake mechanism of a motor vehicle. It will be appreciated that as long as grinding continues by the action of the abrasive belt 46 on the lining, the groove in the lining will be cut, always to the predetermined desired depth until the grinding and grooving operation is completed.

When, for example, the abrasive belt 46 becomes worn and loses its abrasive effectiveness, the screws 60 and 62 are loosened and the compression of the springs 68 and 70 is correspondingly reduced to thereby loosen the clamping members 52a and 52b to facilitate removal of the flanges 92 of the hooks 48 and 50 longitudinally from between these clamping members 52a and 52b. A replacement abrasive belt 46 having hooks 48 and 50 riveted thereto by heat deformed spikes 82 is then mounted on the arbor 9 in the manner heretofore described.

Although various minor modifications of the present invention will become readily apparent to those versed in the art, it should be understood that I wish to embody within the scope of the patent warranted hereon all such embodiments as reasonably and properly come within the scope of my contribution to the art.

I claim:

1. A brake lining grinder and groover comprising a spindle, a cylindrical arbor carried on said spindle and having a slot extending parallel to its axis, a sheet-like member wrapped around said arbor and having an external abrasive surface with edge portions of said sheet-like member extending through said slot and into said arbor, a pair of elongate hooks formed of thermoplastic, synthetic plastic material and extending along the edges respectively of said sheet-like member, and each including an elongate body and a plurality of rivets arranged in spaced relation along said body and upstanding integrally therefrom, said rivets extending through said sheet-like member and thermoplastically deformed into clamping engagement therewith, retaining means carried by said spindle and disposed in said arbor for maintaining said sheet-like member in position on said arbor and having two pairs of opposed flanges, each pair receiving

and retaining one of said hooks therebetween, said retaining means having an aperture aligned generally with said slot, a grooving tool bit having a cutting edge, and means supporting said tool bit on said spindle and projecting through said aperture and said slot with said cutting edge outwardly of the periphery of said abrasive surface.

2. A brake lining grinder and groover comprising a spindle, a cylindrical arbor carried on said spindle and having a slot extending parallel to its axis, a sheet-like member wrapped around said arbor and having an external abrasive surface with edge portions of said sheet-like member extending through said slot and into said arbor, a pair of elongate hooks formed of thermoplastic synthetic plastic material and extending along the edges respectively of said sheet-like member and each including a body of elongate form having a flange and a plurality of spaced rivets upstanding integrally from said body on the opposite side from said flange and extending through said sheet-like member and thermoplastically deformed into engagement with said sheet-like member and clampng said sheet-like member against said body and retaining means carried by said spindle and disposed in said arbor for maintaining said sheet-like member in position on said arbor and having two pairs of opposed flanges, each pair receiving and retaining the flanges of one of said hooks therebetween, said retaining means having an aperture aligned generally with said slot, a grooving tool bit having a cutting edge, and means supporting said tool bit on said spindle and projecting through said aperture and said slot with said cutting edge outwardly of the periphery of said abrasive surface.
